Specification for Design.

Patented Apr. 24, 1917.

Application filed March 6, 1917. Serial No. 152,944. Term of patent 3½ years.

To all whom it may concern:

Be it known that I, EUGENE IRVING HANSON, a citizen of the United States of America, and a resident of New Rochelle, county of Westchester, and State of New York, have invented a new, original, and ornamental Design for a Textile Fabric, of which the following is a specification, reference being had to the accompanying drawing, showing my design.

The drawing shows a face view of a portion of fabric bearing my design.

The color indicated by way of example in the drawing by the shading may be varied without departing from my invention. My design comprises upon a contrasting background stripes *a* composed of substantially square figures *b* with wavy outlines, and with stripes *c*, each of said stripes *c* being composed of a center stripe *d* with

irregular scalloped edges *e* of a color contrasting with the color of said stripe *d*, said stripe *d* having superimposed upon it in a color contrasting with its color substantially heart-shaped figures *f* with wavy outlines, said figures *f* having superimposed upon them irregular figures *g* of a color contrasting with the color of said figures *f*.

The stripes *a* and *c* extend throughout the fabric in one direction and are repeated in alternate arrangement transversely to the said direction.

It is to be understood that my claim includes all substantial equivalents of my design as shown and described.

I claim:

The design for a textile fabric substantially as shown and described.

EUGENE IRVING HANSON.
